EARRING

Edward J. Shea, Brooklyn, N. Y.

Application March 29, 1934, Serial No. 718,037

3 Claims. (Cl. 63—14)

My invention relates to improvements in ear-rings and it consists in the constructions, combinations and arrangements herein described and claimed.

5 An object of my invention is to provide an earring having vacuum cup holding members, and which may be worn without irritation to the ear.

A further object is to provide a device of the kind in which springs or screws are eliminated, 10 thereby simplifying the device.

A further object is to provide an earring which is made partly of metal without temper, and which therefore is not liable to breakage from use, as tempered springs, the flexure of which 15 may be necessary in attaching or detaching the earring.

Other objects and advantages will appear in the following specification, and the novel features of the invention will be particularly pointed 20 out in the appended claims.

My invention is illustrated in the accompanying drawing forming part of this application, in which:

Figure 1 is a plan view of an earring construction showing vacuum cups.

Figure 2 is an edge view of the earring shown in Fig. 1.

Figure 3 is a sectional view showing the earring attached to the ear.

30 Figure 4 is an enlarged detailed view showing one form of vacuum cup, and,

Figure 5 is a detailed view of a modified form of vacuum cup.

In carrying out my invention I provide an ornament such as a pearl 1. This is secured to a strip 2, which is designed to straddle the lobe of the ear, by means of a pin 3 or other suitable connection. In Fig. 3 I have shown the member 2 as provided with a backing 4, to which is secured a vacuum cup 5 of rubber, fibre or other resilient material. The opposite end of the member 2 may be also provided with backing 4 and has a similar vacuum cup 5. These vacuum cups may be cemented, clamped or otherwise secured, 45 without departing from the spirit of the invention. Also the means for securing the backings 4 in place may be made in various ways, such as by bending prongs 6 carried by enlarged portions of the member 2 over the edges of the backings 50 as shown in Figs. 1 and 2.

From the foregoing description of the various parts of the device the operation thereof may be readily understood.

Since the member 2 is not tempered it will bend 55 easily and the vacuum cups 5 may be forced into

close contact with the lobe of the ear, as shown in Fig. 3, and will adhere thereto, thus holding the earring securely.

In Fig. 5 I have shown a modified form in which the concave surface of the cup 5 is provided with bars 7 and prongs 8 of resilient material, the use of these bars and prongs preventing movement or slipping from the desired position.

I am aware that cup-shaped metal pieces have been used in connection with screws to hold ear-rings in position, but such metal pieces are not resilient and the clinging effect is produced through the tightening of the screw. This tends to interfere with the proper circulation of the blood in the ear, whereas the use of the vacuum cup obviates such hindrance to the circulation while at the same time it forms a fastening means that gives comfort to the wearer, and provides a firm and secure attaching means.

I claim:

1. The combination with a flexible connecting member having enlarged end portions, of a backing member secured to said enlarged end portions on one face thereof, a vacuum cup secured to each of said backing members with the concave portions of the cup facing away from said backing members, and an ornament secured to said flexible connecting member on the face of one of said enlarged portions on the opposite side from said vacuum cup.

2. The combination of a flat flexible metal strip having enlarged end portions, a backing member secured to each end portion on one face thereof, a vacuum cup carried by each backing member with the concave face of the cup facing away from the backing member, means carried by said enlarged end portions for retaining said backing members, and an ornament secured to one of said enlarged end portions on the opposite side from the vacuum cup.

3. The combination of a flat flexible metal strip having enlarged end portions, a backing member secured to each end portion on one face thereof, a vacuum cup carried by each backing member with the concave face of the cup facing away from the backing member, integral prongs carried by the enlarged end portions and being bent over the edges of the backing members for retaining them in position, and an ornament secured to one of said enlarged end portions on the opposite side from the vacuum cup.

EDWARD J. SHEA.
